TRAY ELEVATION ADJUSTMENT

Lloyd L. Anderson, Grand Rapids, Robert E. Johnson, Marne, and Robert G. Metzger and Andrew J. Van Noord, Grand Rapids, Mich., assignors to Jervis Corporation, Grandville, Mich., a corporation of Michigan

Filed July 3, 1958, Ser. No. 746,482

8 Claims. (Cl. 211—146)

The present invention relates to a tray or shelf adjustment and more particularly to an elevation adjustment for trays assembled in vertical spaced apart relationship on a threaded vertical post. Still more specifically the present invention comprises a novel selectively reversible ratchet device which self-centers when not in use and which is normally biased to a preselected position so as to be non-interfering with respect to the use of shelving served.

In household shelving it is frequently necessary that the spacing between shelves be adjusted. Heretofore such adjustment has been accomplished by incremental stages using marginal clips which coact with clip tracks running vertically up adjacent walls. In rotatable shelf structures devices of various types have been used which move upward and downward on a vertical post. In some instances the post is stationary and the shelving is rotated in cooperation with a thread on the post to raise or lower selected shelves. In other instances the post is rotated and threading on the post cooperates with a support bracket to raise or lower the shelving. Such devices have caused considerable difficulty in that they cluttered the storage area of the shelf and presented difficult bearing problems in actual applications where the post or column was located substantially at the center of the shelf served. In addition, the prior shelving adjustments were unhandy or clumsy to use. Where a threaded post was rotated, provision was required to disengage selected shelves and engage others for adjustment. The stationary post systems required full rotation of the shelf or shelf lifter element for adjustment.

In plural shelf refrigerators, for example, these problems are greatly emphasized since it is desirable that the shelf be fully useable and that a minimum of storage space be wasted.

Accordingly it is one of the objects of the present invention to provide adjustable side mounted swing out shelving for refrigerator cabinets and the like.

Another object is to provide an adjustment for such swing out shelving which is biased out of the way when not in use.

Another object is to provide an adjustment which will not require rotation of either the shelf or the support post and wherein a ratchet and pawl system allows reversible finger tip control for each individual shelf.

Another object of the present invention is to provide a shelf-adjustment having positive control over both the lowering and raising of associated shelves.

Another object is the provision of a shelf elevation adjusting feature wherein the shelves served are detent controlled upon swing in.

Other objects including simplicity, economy, and trouble free construction will be more appreciated by those skilled in the art as the description proceeds.

In the drawings:

Figure 1 is a partial front elevational view of a pair

2

of shelves mounted on a vertical threaded post and the shelves supported by elevation adjusting members.

Figure 2 is a partial top plan view of the structure shown in Figure 1 and taken on line II—II of Figure 1 illustrating the handle position of the elevation adjusting members in "rest" position biased in close proximity to the case wall, and also showing the handle positioned as for raising or lowering.

Figure 3 is a top plan partially cut away view of the elevation adjusting member of the present invention.

Figure 4 is an elevational section view taken on line IV—IV of Figure 3 and illustrating the cooperation between component elements in the assembled elevation adjusting member.

Figure 5 is a perspective exploded view of the elevation adjusting member shown in Figure 4 and showing the individual elements in their relationship to a threaded vertical column.

Figure 6 is a partial plan view showing the "neutral" pawl position in relationship to the adjusting nut, the phantom line showing movement of pawl against the pawl spring.

Figure 7 is a partial plan view showing the position of the pawl in relationship to the adjusting nut for moving the shelf member downward, the phantom line indicating travel of the pawl against the pawl spring on the disengaged portion of the stroke.

Figure 8 is a partial plan view showing the position of the pawl in relationship to the adjusting nut for moving the shelf member upward, the phantom line indicating retraction of the pawl against the pawl spring in the disengaged portion of the stroke.

Figure 9 is a section view taken on line IX—IX of Figure 4, and indicates the return spring bias arrangement in the ratchet portion of the actuator.

General description

In general a housed nut engages a threaded non-rotatable vertical column or post. A handle portion extends outwardly from the housing. The handle portion contains a selectively reversible pawl assembly biased normally into a "neutral" position against the ratchet exterior of the housed nut. A partially split sleeve is provided having a flanged base which axially surrounds or houses a portion of the threaded vertical column. The sleeve provides mounting means for a shelf member. An assembly and keeper ring peripherally secured to the housing retains the sleeve in axial engagement with the nut. An annular locating spring ring is positioned between the flange of the sleeve and the keeper ring in flexural engagement with the sleeve and housing. Beneath the nut, a thrust washer having upwardly extending detent points, engages the lower face of the nut, the detent points extending into the groove circle of the ratchet portion of the nut. This arrangement retards any tendency of the nut to move in the non-thrust portion of the pawl stroke. The split sleeve provides a mount for shelving. The shelving fits over the sleeve in bearing contact therewith. The sleeve, by reason of its being secured to the housing as well as the shelf or platform, provides a positive movement link to the shelf. The sleeve is keyed to the vertical post as is the thrust washer with its detent faces. This keying prevents rotation of the sleeve or detent washer.

When in use, the housed ratchet and pawl structure is engaged by means of the sleeve with the shelving on the post. The position of the device is spring biased to a preselected out-of-the-way location. If the handle were to be rotated reciprocably in a horizontal plane, no motion would be imparted to the associated shelf. If the pawl structure is rotated to either the "raise" or

"lower" position and the pawl structure is rotatably reciprocated in a substantially horizontal plane, then, depending upon the selected rotation of the pawl structure, the shelf is moved upwardly or downwardly. The shelf does not rotate with this action, but it may be disengaged from detent positioning for swing out on the vertical post.

Specific description

Referring more specifically to the drawing, Figure 1 shows a plurality of horizontal shelves 11 in vertical parallel spaced apart relation on a threaded vertical post 12. Supporting each shelf 11 at its hub 13 is an actuator device 14. In Figure 2 the normal biased position of the actuator 14 is shown in relation to swing out shelves 11 mounted adjacent to the door facing of a cabinet 15. Suitable top and bottom sockets 16 and 17 secure the vertical threaded post 12 against rotation and in fixed relationship to the cabinet 15.

The actuator assembly 14 is best shown with reference to Figure 5 illustrating the component parts.

The hub 13 of shelf 11 is integral with shelf 11 and is smoothly recessed to mount over the post 12, and to bear against a tubular extension 18 of a flanged sleeve 19. The annular base 20 of the hub 13 is provided with raised segments 21 and 22 which, as will be seen, cooperate with the raised flange segments 23 and 24 on the flange 25 of the sleeve 19. The cooperative interrelationship of the parts is best shown in Figure 1. On the outer periphery of the flange 25 on the sleeve 19, is a spring engaging post 25a. The tubular extension 18 of the sleeve 19 is split as by slots 28 and 29 for a substantial portion of its length and the internal bore of the tube 18 is upset as by the spline 26 to matingly engage the key way 27 longitudinally provided in the threaded post 12. The slots 28 and 29 allow the hub 13 to be assembled over the tubular extension 18. Lips 30 and 31 at the upper periphery of the tubular extension 18 thus flare out over the hub 13 securely interlocking hub 13 and sleeve 19. The normal outside diameter of the sleeve 19 is substantially equal to the inside diameter of the hub 13. The slots 28 and 29 in the sleeve 19 admit of collapse sufficient to allow the lips 30 and 31 to take a shape conforming substantially to the inside diameter of the hub 13. In this manner the sleeve 19 is pushed into the hub 13 and the lips 30 and 31 expand to perform a retaining function retaining the sleeve 19 on one end while the flange 25 retains it on the other end of the hub 13. An assembly ring or keeper 32, which is generally annular in shape is interposed around the sleeve 19 and the hub 13 (Figure 4). The assembly ring 32 comprises a short tubular portion 33, and an upper peripheral and integral flange 34. The flange 34 is cut away at 35 to provide, as will be seen, assembly access and locking means against the spring 36. The spring 36 has a clearance diameter in relationship to the tubular portion 33 of the ring 32. The ends 37 and 38 of the spring 36 are bent one upward and one downward. The spring 36 is thus coaxial with the assembly ring 32 and is provided with an upwardly extending end 37 and downwardly turned end 38. The function of the attachment of the upwardly and downwardly turned spring ends 37 and 38 will be better appreciated as the description proceeds. The extending ends 37 and 38 of the spring 36 are located to lock engage opposite edges of the post 25a of sleeve 19 as best shown in Figure 3.

A nut 39 is provided, having an upper annular smooth bearing surface 40 and internal threads 41 for coaxial engagement with the threaded vertical post 12. The lower shoulder portion of the nut 39 (lower with respect to Figure 5) is serrated, the serrations 42 being spline-like and extending a substantial length of the nut 39. The fit of nut 39 to the threaded post 12 is of the "running" class. These serration recesses 42 are engageable over bumps 43, provided on the upper surface of the washer 44. The washer 44 is provided with an opening 45 so as

to fit over the threaded post 12. A radial extension 46 toward the center of the washer 44 is located to engage the keyway 27 in the threaded post 12. A spring washer 47 bent transversely of its axis is located beneath the washer 44.

The operating handle 48 provides housing means for the actuating assembly. A major recess 49 is provided in the housing or handle 48 coaxial with the sleeve 19 and post 12. A minor recess 50 through the radial extension 51 of the handle 48 provides housing means for the ratchet operating assembly 52, as will be seen. The minor recess 50 opens transversely into the major recess 49.

The major recess 49 comprises a through opening having a lower shoulder 53 (Figure 4) which receives the spring washer 47, the washer 44 and the nut 39. The serrations 42 of the nut 39 are thus located adjacent the recess 50. An intermediate shoulder 54 of larger diameter than the lower shoulder 53 receives the flange 25 of the sleeve 19. The return spring 36 nests in clearance relationship around the keeper ring 32. The flange 34 of the ring 32 slips into the annular groove 55 in a twisting action made possible by the cut-away portion 35 and the relief 56 in the handle 48 adjacent the major recess 49. When assembled the tubular extension 33 of the ring 32 bears on the flange 25 of the sleeve 19 and the return spring 36 is attached at both ends to the housing or handle 48 and to the sleeve post 25a. Attachment to the handle 48 is accomplished by reason of the radial inwardly facing barrier 57 which coincides with the sleeve post 25a when the spring 36 is tensionally assembled as best shown in Figure 3. The whole sleeve assembly is axially positioned over the threaded post 12.

As will be appreciated the interrelationship between spring 36, post 25a and barrier 57 under tension establishes the normal bias location of the handle 48 in radial relationship from the threaded post 12. Thus as the handle 48 is rotated in either a clockwise or counterclockwise relation the spring return is to the preselected position aligning post 25a and barrier 57.

The minor recess 50 axially provides a mounting for the ratchet assembly 52. As best shown in Figures 3 and 4 the ratchet assembly 52 comprises a knob 58 having an axially recessed cut away sleeve extension 59. A shaft 60 is fixedly attached to said knob 58 and extends axially therefrom. Over said shaft 60, and in the cut-away sleeve extension 59 of knob 58, is a knob biasing coil spring 61, the ends 62 and 63 of which extend to shoulder against the semi circular retaining element 64 on one side of the minor recess 50 (Figure 9). An annular spring retainer 65 on the shaft 60 secures the spring 61 in position against axial dislodgment and provides a pressure seat for the pawl spring 66. The pawl spring 66 is over the shaft 60 and is of the compression type bearing against the spring retainer 65 at one end and the pawl 67 on the other end. The pawl 67 is mounted on the shaft 60 so as to reciprocate on the shaft 60 against the pawl spring 66. A pin 68 through the shaft 60, proximate to its end extends radially into a pawl slot 69 provided in the pawl 67 so as to provide rotational coordination as between knob 58 and pawl 67. Thus, in the normal position, the pawl 67 is fully extended on the shaft 60. The pawl 67 is cylindrical at its base with its forward end truncated. The truncation, 70 results in a forwardly extending tip 71 which in plan view is conic in form.

A semi circular annular groove 72 is provided in the shoulder 73 of the knob 58. This provides stop means upon rotation of the knob 58 through 90 degrees in either direction on its axis from the normal rest position. A screw 74, through the radial extension 51 of the handle 48 extends into the groove 72. The section view of Figures 3 and 4 best illustrates the described interrelationship of the pawl assembly in the extension 51. When the handle 48 is in its normal position the pawl 67 extends into the serrations 42 of the nut 39, but as will be ap-

preciated, reciprocation of the handle 48 does not move the nut 39 on the threaded post 12 since the conic tip 71 slips over the shoulders of the serrations 42 with the pawl 67 reciprocating on the shaft 60 against the spring 66 (Figure 6). Clockwise rotation of the knob 58, however, positions the pawl 67 for moving engagement with the serrations 42 of the nut 39. As the handle 48 is reciprocated the stroke in one direction moves the nut 39 through the arc of the handle movement and on the return of the handle 48 allows the pawl 67 to override the serrations 42 (Figure 8). As illustrated, this raises the entire assembly and the associated shelf 11. Manually applied counterclockwise movement of the knob 58 reverses the position of the pawl 67 for lowering action on the nut 39 (Figure 7). Any tendency on the part of the pawl 67 to carry the nut 39 with it on its return movement is resisted by reason of the washer 44 which is keyed to the threaded post 12 and whose bumps 43 resiliently engage the serrations 42 to resist movement on the nut 39. This resistance is aided by the bearing load supplied by the spring washer 47. Upon release of the handle 48 the extension 51 obeys its spring bias to return to a selected out-of-the-way position, and the pawl 67 and knob 58 are returned to neutral position.

The unique construction of the described actuating structure provides positive upward movement of the shelves 11 inasmuch as the nut 39 directly bears on the flange 25 of the sleeve 19. Thus clockwise rotation of the nut 39 raises the shelf 11 which is secured to the sleeve 19. As the nut 39 is rotated in a counterclockwise manner the handle housing 48 is drawn downwardly with the nut and the ring 32 transmits down-pulling force to the flange 25 of the sleeve 19 thereby urging the shelf 11 downwardly in a positive manner.

The raised segments 21 and 22 on the hub 13 of the shelf 12 (phantom line in Figure 1) nest between the raised segments 23 and 24 of the flange 25 of the sleeve 19. This provides detent locating control over the swing out of shelf 11. This is the position, for example, when the shelf 11 is at rest in the cabinet. When the shelf 11 is rotated outwardly, the raised segments 21 and 22 ride over the segments 23 and 24 on the flange 25, their relative nesting positions at rest being overcome by the swing-out motion. When the shelf 11 is returned, the interlock between segments 21, 22 and 23, 24 is re-established and the shelf 11 is provided with a resistance to swing-out which can be manually overcome. The hub 13 thus is rotatable on the tubular portion 18 of the sleeve 19. The sleeve 19 and washer 44 are keyed to the fixed threaded post 12.

Operation

Typical illustration of operation is to be found in considering, for example, a modern refrigerator where the increase in capacity of the cabinet makes certain portions of the refrigerator shelves relatively inaccessible. In such a setting a fixed threaded post 12 is vertically oriented adjacent one of the door openings. The post 12 thus provides a pivot about which shelves 11 can be swung out clear of the enclosure of the cabinet 15 (Figures 1 and 2). As desired the post mounting area may be completely recessed in the cabinet wall so as not to interfere with storage. Each shelf 11 is thus cantilevered from the post 12. The hub 13 of each shelf directly bears upon an actuating assembly as desired. In normal use the extension 51 of the handle 48 is positioned out of the way and against the wall of the cabinet 15. This position obtains by reason of the normal spring bias applied through spring 36. The normal bias on the knob 58 is also effective so that chance rotational reciprocation has no effect on movement of the shelf up or down. However, simple manual movement of the knob 48 through an arc of ninety degrees prepares the pawl 67 for moving engagement with the serrated ratchet surface of the nut 39. Now rotational reciprocation of the handle 48 ac-

complishes selected movement or adjustment of the shelf 11 up and down on the threaded post 12. Convenient marking of "Raise" on the upper surface of the knob 58 and "Lower" on the lower surface of the knob 58 provides visual means for the housewife to easily comprehend the selected position for adjustment. Ninety degree rotation of the knob 58 in a clockwise direction brings "Raise" into visual prominence. Ninety degree counterclockwise rotation of the knob 58 positions "Lower" for visual prominence. This function is best described visually with reference to Figures 6, 7, and 8. This arrangement is, of course, applicable to a right hand thread and mating nut. Using a left hand thread, as may in some instances be desirable, would require a reversal of the recited orientation.

The handle 48 is economically prepared using an accurate die casting thereby substantially eliminating complicated machining. The sleeve 19 is made preferably from a resilient resin material such as that commonly known as nylon or the like. The nut 39 is preferably cast from a filled phenolic resin material selected for good dimensional stability in a wide thermal range. The knob 58 and its associated shoulder 73 and cut-away sleeve 59 is integrally die cast. The external parts are ornamentally chromium plated. The functioning of the described adjustment is smooth and the cantilever distribution of shelf stresses are neatly transmitted to the vertical threaded post 12. The described structure permits independent shelf height adjustment for each shelf 11 in a plural relation on a common threaded post 12.

Elevation adjustment is thus accomplished in a manner using an accurate movement short of complete rotation. The resin materials in the structure dampen metallic sounds during actuation.

Having thus described our invention other modifications will be immediately apparent to those skilled in the art and such modifications are intended to be included herein in limited only by the scope of the hereinafter appended claims.

40 We claim:

1. In a shelf adjustment device for swing out shelves, the combination comprising: a shelf; a hub portion on said shelf having detent means in association therewith; a sleeve through said hub having mating detent means in support relationship to said hub and in positive grip thereto; a nut in axial bearing relationship to said sleeve; and having ratchet serrations; a housing around said nut and holding said sleeve; pawl means through said housing in selected reversal relationship with said nut; and a fixed threaded post keyed to said sleeve and in threaded engagement with said nut.

2. In a shelf adjustment device for swing out shelves, the combination comprising: a shelf; a hub portion on said shelf having detent means in association therewith; a sleeve through said hub having mating detent means in support relationship to said hub and in positive grip thereto; selectively reversible ratchet and pawl means in positive raising and lowering engagement with said sleeve; a spring locating bias in engaged relationship with said sleeve; a second spring bias centering the pawl of said ratchet and pawl means in a neutral position; and a fixed threaded post keyed to said sleeve and in threaded engagement with the ratchet of said ratchet and pawl means.

3. In a shelf elevation adjusting device for use on a fixed threaded vertical post, the combination comprising: a nut having a cylindrical ratchet serrated external surface and in threadable relationship to said post; a detent bearing washer keyable to said post; a spring washer bearing upwardly on said keyed washer; a housing defining a major opening and a transverse minor opening, said major opening seatably receiving said spring washer, said keyed washer, and said nut; a flanged tubular sleeve axially positioned in said major opening, bearing on said nut, and being split to deform inwardly; detent segments

extending from said flange of said sleeve; a sleeve post extending upwardly from the periphery of said flange; a keeper ring seated in said major opening and bearing downwardly on said flange of said sleeve; resilient means around said keeper ring; a barrier integral with said housing and projecting into said major recess and coinciding in position with said sleeve post, both said sleeve post and said barrier retaining ends of said resilient means; and normally neutral selectively reversible pawl means extending axially through said minor opening in said housing in resilient contact with said ratchet face of said nut.

4. A self neutralizing selectively reversible ratchet and pawl mechanism comprising: a housing defining a major axis recess and a minor axis recess; a sleeve in said major recess, the inner surface of which is upset for gripping engagement; ratchet means in said major recess against which said sleeve bears; detent means in resilient engagement with said ratchet means resisting movement of said ratchet; spring retaining means around said sleeve and centering said sleeve in a normal position with respect to said housing; and a pawl assembly axially through said minor opening in said housing said pawl assembly including a selecting knob, a shaft on said knob, a normal position biasing spring on said shaft and in engagement with said housing and said knob, a keeper, a compression spring acting on said keeper and on said shaft, a slotted pawl on said shaft retained thereon for axial reciprocation and rotatable with said shaft, and means through said housing

and engaging said knob limiting clockwise and counter-clockwise rotation of said knob and attached shaft and pawl; said pawl in resilient engagement with said ratchet surface, and movably engaging said ratchet when said knob is rotated against the bias of said spring and said housing is rotationally reciprocated.

5. In a structure substantially as in claim 4 the combination wherein said sleeve is in keyed relationship to a fixed and threaded post and wherein said ratchet is threadably engageable with said post.

6. In a structure substantially as in claim 5 the combination wherein said sleeve pivotally retains a shelf through an off-center hub integral with shelf.

7. In a structure substantially as in claim 6 the combination wherein said sleeve is partially longitudinally split to receive said shelf.

8. In a structure substantially in claim 7 the combination wherein said split sleeve is provided with lips which expand with said split sleeve upon assembly to provide a positive grip on said shelf.
